Patented Nov. 23, 1920.

FIG. 1

INVENTOR=
Walter C. Reed,
By E. D. Chadwick,
Attorney.

UNITED STATES PATENT OFFICE.

WALTER C. REED, OF DALTON, MASSACHUSETTS, ASSIGNOR TO PHILIP W. GOEWY, OF PITTSFIELD, MASSACHUSETTS.

KEY-ACTION.

1,360,019.

Specification of Letters Patent. Patented Nov. 23, 1920.

Application filed October 25, 1916. Serial No. 127,569.

To all whom it may concern:

Be it known that I, WALTER C. REED, a citizen of the United States, residing at Dalton, in the county of Berkshire and State of Massachusetts, have invented certain new and useful Improvements in Key-Actions, of which the following is a specification.

My invention relates to key actions for musical instruments in which the various tones are sounded through the agency of electric circuits controlled by the several keys of a key board, and is particularly intended to provide an improved key action for pipe organs of the character just referred to. In such actions it is desirable, in order to secure certainty and smoothness in the playing of the instrument, to have the parts so constructed that a greater pressure will be required to commence the depression of a key than to continue its downward movement or to hold it in the depressed position, and it is also desirable to have this pressure exactly the same for all keys, so that the "touch" will be uniform. The present invention provides a key action having the characteristics above referred to and also having certain other advantageous features hereinafter described.

30 In the accompanying drawing:

Figure 1 is a plan view showing several adjacent key actions embodying my invention, as preferably constructed; and

35 Fig. 2 is a side elevation of one of the actions illustrated in Fig. 1.

In Fig. 1 of the drawing, I have illustrated in part three consecutive organ keys 2, of which the rear portions only are shown for the reason that the keys may be of any 40 suitable construction. In the present case each key 2 is pivotally supported between its ends in the usual manner, so that when its front end is depressed its rear end will be elevated, and it is to be assumed that each 45 key in the key board is provided with an action like that hereinafter described.

The circuit-controlling devices operated by the keys 2 are represented as consisting of spring contact wires or fingers 3 secured 50 at their rear ends to a wooden strip 4 whereby they are sufficiently insulated from one another and from which they extend forward over a metallic contact bar 5 carried by insulated brackets of which one is shown

at 6. These brackets are secured to the top 55 of a fixed support 7 which extends transversely behind all the keys and carries the strip 4. Each of the wires 3 is provided at its rear end with a loop 8 adapted to be connected to a corresponding circuit wire, 60 (not shown,) to which current will be transmitted through the wire 3 from the contact bar 5 whenever a short silver sleeve 9 carried by the wire 3 makes contact with said bar, the latter being supplied with current 65 from any suitable source. Any desired number of wires 3, from one upward, may be employed in connection with each key 2, but ordinarily there are several such wires for each key, for reasons which are not material to the invention herein set forth.

The spring action of the wires 3 is such that they tend to make contact with the bar 5, but normally the several wires 3 corresponding to each key are held out of contact with the bar 5 by means of a lever 10, the rear end of which extends horizontally beneath the free ends of said wires and carries a sleeve 11 of felt or the like on which the wires rest, while its front end is supported by the rear end of the corresponding key 2, resting preferably on a felt or leather pad 12 secured thereto. Between its ends each lever 10 is mounted on a transversely-extending pivot 13 carried by a bracket 14 85 which is secured to the front face of the support 7 and also carries a screw 15 passing through and vertically adjustable in a laterally extending flange on the top of the bracket, said screw being provided with a 90 lock nut 16 for maintaining it in any given position of adjustment. To the lower end of the screw 15 is attached the rear end of a tension spring 17 which extends forward below the pivot 13 and is attached at its 95 front end to the lever 10, so that it tends to depress the front end of the lever and hold the front end of the corresponding key 2 in its normal or elevated position. When the key is in this position the corresponding 100 spring wires 3 are held slightly above the contact bar 5, as shown in Fig. 2, but when the front end of any key is depressed in the act of playing the elevation of its rear end acts through its lever 10 to lower the corresponding wires 3 into contact with the bar 5, thus completing the several circuits 105 through said wires and causing the pipes

controlled thereby to be sounded, subject to such further control as may be provided elsewhere.

It will be evident that as the rear end of any key 2 rises the force exerted by the corresponding spring 17 on its lever 10 and tending to move the forward end of the latter downward will continually grow less, due to the approach of the spring to a dead center position with respect to the pivotal axis of the lever. The parts are so arranged, however, that this dead center position is never actually reached, but the spring at all times exerts sufficient force on the lever to 15 elevate the front end of the corresponding key when the latter is released. It follows that when the front end of the key is depressed in playing the instrument, the force required to depress it is greatest at the beginning of the depression and thereafter decreases until the key is fully depressed. Uniformity of action of all the keys is obtained by means of the screws 15, by the upward or downward adjustment of which the 20 leverage of the corresponding springs 17 on their levers 10 may be minutely varied and caused to be exactly alike with respect to the effect of the several springs on the respective keys.

30 It will be seen that my invention provides a key action which not only has the desirable characteristics above referred to but is also simple and inexpensive in construction, is very compact, is easily adjusted with great accuracy, and is not likely to have its adjustment disturbed or otherwise get out of order. My key action also has the advantages that the organ keys do not have to be provided with special parts other than the pads 12 and are not mechanically connected to the parts which they operate, so that all the parts of the action can be assembled and then applied to an existing key-bank without difficulty and any key can be taken out for repairs without disturbing the action.

While I prefer to employ the spring wire contacts illustrated for the purpose of controlling the respective electric circuits it 50 will be understood that various other forms of circuit controllers may be employed instead, if desired, and that the construction of the action may be modified in various ways without departing from my invention.

55 I claim:

1. In a key action, the combination of a key, a circuit controller, a lever interposed between the key and the circuit controller, separate from but normally in engagement with said key, and a spring connected to the lever and tending to hold the front end of the key in elevated position, the spring being arranged to exert on said key a force which diminishes when the front end of 65 the key is depressed.

2. In a key action, the combination of a key, a circuit controller, a lever interposed between the key and the circuit controller, separate from but normally in engagement with said key, a spring connected to the lever and tending to hold the front end of the key in elevated position, the spring being arranged to exert on said key a force which diminishes when the front end of the key is depressed, and means for regulating 75 the action of said spring.

3. In a key action, the combination of a key, a circuit controller, a pivotally-mounted lever interposed between the key and the circuit controller, separate from but normally in engagement with said key, a spring connected to said lever and extending in such direction with respect to its pivotal axis as to exert on the key a force tending to elevate the front end of the latter and 85 diminishing when said front end of the key is depressed, and means for varying the distance between the line of action of the spring and the pivotal axis of the lever.

4. In a key action, the combination of a key, a pivotally-mounted lever having its front end resting freely on and supported by the rear end of the key, a tension spring connected at its front end to said lever and extending rearward in a direction passing beneath the pivotal axis of the latter, a vertical adjusting screw to which the rear end of said spring is secured, and a circuit-controller arranged to be operated by said lever.

5. In a key action, the combination of a key, a pivotally-mounted lever having one of its arms resting on the key, a spring contact finger resting on the other arm of the lever and normally held thereby in elevated position, a contact bar located beneath said spring finger in position to make contact with the latter when lowered, and a spring acting on said lever in such direction as to exert on the key a force tending to elevate 100 the front end of the latter and diminishing when said front end of the key is depressed.

6. In a key action, the combination of a key, a fixed support located behind the same, a lever pivotally-mounted on said support 115 and having its front end resting freely on the rear end of the key, a plurality of independent spring contact fingers located side by side with their free ends resting on the rear end of the lever and normally held 120 thereby in elevated position, a contact bar located beneath said spring fingers in position to make contact with the latter when lowered, and a spring connected to said lever and tending to depress the front end 125 of the latter.

Signed by me at Boston, Massachusetts, this seventeenth day of October, 1916.

WALTER C. REED.
